Patented Feb. 5, 1895.

UNITED STATES PATENT OFFICE.

WILLIAM J. STEWART, OF CHICAGO, ILLINOIS.

FEEDING MECHANISM FOR SEWING-MACHINES.

SPECIFICATION forming part of Letters Patent No. 533,566, dated February 5, 1895.

Application filed December 26, 1893. Serial No. 494,776. (No model.)

To all whom it may concern:

Be it known that I, WILLIAM J. STEWART, a citizen of the United States, residing at Chicago, in the county of Cook and State of Illinois, have invented certain new and useful Improvements in Sewing-Machine Feed Mechanism; and I do hereby declare the following to be a full, clear, and exact description of the same, reference being had to the accompanying drawings, forming part of this specification.

The present invention relates to certain improvements upon the subject matter of Letters Patent No. 460,730, issued to me October 6, 1890, for feeding mechanism for sewing machines; the object of the present improvement being to provide a simple and effective construction and arrangement of parts, affording cheapness in manufacture, and a ready and convenient adjustment to effect any required length of stitch; the present invention consisting in the construction and combination of parts by which such results are obtained, and as will hereinafter more fully appear and be more particularly indicated in the claims. I attain such objects by the construction and arrangement of parts illustrated in the accompanying drawings, in which—

Figure 1 is a perspective view of a sewing machine illustrating the general arrangement of my present invention; Fig. 2, an inverted plan view of the same; Fig. 3, a vertical section at line $x-x$ Fig. 2, and Fig. 4, a detail perspective view of the feed bar of the sewing machine constructed in accordance with the present invention.

Similar numerals of reference indicate like parts in the several views.

Referring to the drawings 1 represents the "four motion" feed bar, by which the feeding of the material during the sewing operation is effected.

As in my former patented construction the required motion is communicated to the feed bar 1, by the longitudinally extending bar or rod 2, journaled at its forward end in a bearing bracket 3, located at a point forward of the feed bar 1, the journal being formed by a spherical end on the bar or rod 2, engaged by a holding screw 4, the end of which is made cup shaped as in my former invention. A gyrating motion is imparted to the rear end

of the bar or rod 2, by the link connection 5, the upper end of which is formed with an eccentric yoke 6, engaging an operating eccentric 7, on the driving shaft 7', of the machine, the lower end of the link connection 5, being provided with cylindrical eye 8, to receive the spherically formed rear end of the gyrating shaft or rod 2.

In the construction shown the link connection 5, is slotted vertically as shown, and in the vertical slot 9, thus formed a vertically adjustable pivot pin 10, engages to form a variable pivot for such link, for the purpose hereinafter set forth. The pin 10, is attached to a vertically adjustable slide 11, moving in a guide slot 12 in the vertical arm of the machine and adapted to be secured at the required adjustment by means of a clamping screw 11'. With this construction, the circle of gyration of the lower end of the link 5, in a vertical plane will remain constant, regardless of the adjustment of the pivot pin 10, and consequently the "up" and "down" movements of the four motion feed bar 1 will remain constant; the adjustment of the pin 10 affecting the gyration of the before mentioned parts in a horizontal plane, increasing as the pin 10, is adjusted upwardly toward the operating eccentric, and decreasing as such pin is adjusted downwardly away from the eccentric. By this means the "backward" and "forward" movements of the "four motion" feed bar are regulated and adjusted to suit any particular requirement without affecting the up and down movements of such feed bar, which remain constant at all times.

In the present invention connection is made between the feed bar 1 and the gyratory shaft 2, by means of a bracket piece 13, attached to said bar and having a rearwardly extending arm 14, the rear end of which is bent upwardly and forked to embrace the gyratory shaft 2, as shown.

In the drawings 15, is the ordinary shuttle lever receiving motion through lever 16, from the operating eccentric 17, on the main driving shaft as usual.

Having thus fully described my said invention, what I claim as new, and desire to secure by Letters Patent, is—

1. A feeding mechanism for sewing machines comprising in combination, the ful-

crummed four motion feed bar 1, a gyratory shaft 2, journaled at a point forward of the feed bar, and bearing against the under side of the same, a bracket piece 13, fixedly secured to the feed bar, and having a rearwardly extending forked arm 14 engaging the gyratory shaft 2, and means for imparting a gyratory motion to the rear end of the shaft 2, substantially as set forth.

10. 2. A feeding mechanism for sewing machines, comprising in combination the fulcrumed four motion feed bar 1, a gyratory shaft 2, journaled at a point forward of the feed bar, and bearing against the under side of the same, a bracket piece 13, fixedly secured to the feed bar, and having a rearwardly extending forked arm 14 engaging the gyratory shaft 2, an operating eccentric on the main shaft, a slotted connecting link, one end 15 of which engages the eccentric, and the other end the rear end of the gyratory shaft 2, a vertically adjustable slide moving in guide slot in the main frame, and carrying a pivot pin engaging in said slotted link and forming a variable fulcrum for the same, substantially as set forth.

25. 3. A feeding mechanism for sewing machines, comprising in combination, the fulcrumed four motion feed bar 1, a gyratory shaft 2, journaled at a point forward of the feed bar and bearing against the under side of the same, a bracket piece 13, fixedly secured to the feed bar, and having a rearwardly extending forked arm 14 engaging the gyratory shaft 2, an operating eccentric on the main shaft, a slotted connected link one end 30 of which engages the eccentric, and the other end the rear end of the gyratory shaft 2, a vertically adjustable slide moving in guide slot in the main frame, and carrying a pivot pin engaging in said slotted link and forming a variable fulcrum for the same, substantially as set forth.

In testimony whereof witness my hand this 16th day of December, 1893.

WILLIAM J. STEWART.

In presence of—
ROBERT BURNS,
JAMES LAVALLIN.
